UNITED STATES PATENT OFFICE.

CHARLES J. McHUGH AND DURWARD S. RIVERS, OF INDIANAPOLIS, INDIANA.

POWER-PROPELLED BOAT.

Application filed April 17, 1922. Serial No. 553,626.

To all whom it may concern:

Be it known that we, CHARLES J. McHUGH and DURWARD S. RIVERS, citizens of the United States, residing at Indianapolis, in the county of Marion and State of Indiana, have invented a new and useful Power-Propelled Boat, of which the following is a specification, reference being had to the accompanying drawings and to the letters and figures of reference marked thereon.

This invention relates to toy boats and similar vessels designed to float in water, and has reference more particularly to means for propelling such water-craft.

An object of the invention is to provide an improved toy boat which shall be so constructed as to resemble a motor boat propelled by an explosion engine, and to imitate such motor boat in operation without requiring engine machinery or mechanism having movable parts entailing structural cost and repair expenses.

Another object is to provide an improved toy boat which shall be of such design as to permit of manufacture at small cost, and which shall be educational and attractive and be safe and efficient in operation.

A further object is to provide an improved apparatus for the propulsion of toy boats in water which shall be suggestive of an explosion engine in appearance and operation, and free from complications and not liable to become deranged or require repairs, and which shall be adapted to be simply and easily operated and be durable and economical in use.

With the above-mentioned and other objects in view, the invention consists in certain novel propelling apparatus constructed in imitation of an explosion engine and having novel features of construction, and in improved toy boat structure, and also in the parts and combinations and arrangements of parts as hereinafter particularly described and further defined in the appended claims.

Referring to the drawings, Figure 1 is a side elevation of an improved toy boat provided with the improved propelling system; Fig. 2 is a top plan of Fig. 1; Fig. 3 is a fragmentary longitudinal sectional elevation illustrating important features of the invention, on an enlarged scale; Fig. 4 is a fragmentary top plan of the boat and its propelling means, partially in section; and,

Fig. 5 is a transverse section approximately on the line V—V in Fig. 3.

In the different figures of the drawings, similar reference characters indicate like elements or features of construction herein referred to in detail.

An embodiment of the invention in a preferred form comprises a boat hull which has a keel 1, bottom portions 2 and 3, main side portions 4 and 5, a bow 6, and a stern 7 provided with a suitable rudder 8, all preferably composed of metal.

A boiler or a pair of boilers and what may be termed "engines" are provided and arranged so as to operate most advantageously for the purposes intended. The boilers preferably comprise fire-box side leg sheets or plates 9 and 10 that are inclined each towards the other, their lower edges being suitably spaced apart and having crown sheet portions 11 and 12 extending upward therefrom and each towards the other, from which vertical plates 13 and 14 extend respectively.

Outer leg sheets or plates 15 and 16 are arranged outside and beyond the fire-box sheets respectively and are connected thereto by means of bottoms 17 and 18 respectively, curved top portions 19 and 20 extending upwardly from the outer plates and over each towards the other, being designed to imitate an explosion engine crank case from which extend upright side members 21 and 22 respectively that are fluted to imitate or suggest explosion engine cylinders, other side members 23 and 24 extending upward therefrom and being shaped in imitation of valve chests, constituting shell portions of boilers having heads 25 and 26 respectively so as to hold water in the main portion, and heads 27 and 28 to hold water and steam in the upper portion or engine, the "engine" portion of the boilers having tops 29 and 30 respectively to prevent the escape of steam.

Preferably the tops are covered by means of a cap 31 having an inclined ridge 32 thereon in imitation of a water circulating conduit, the cap extending over and covering the heat space which is formed between the plates 13 and 14. Deck plates 33 and 34 are arranged between the main portion 4 and the plate 15, and the main portion 5 and the plate 16, respectively, the deck plates preferably being perforated. A transverse

partitional plate 35 is arranged forward of

90

100

105

110

the boiler and engine and an apertured partitional wall plate 36 is arranged behind the boiler and engine. A deck plate 37 is arranged in the rearward portion of the 5 hull and has side portions 38 and 39 that extend forward to the partition 36. The bottoms 17 and 18 of the boilers preferably rest on the bottom portions 2 and 3 of the hull or are located in proximity thereto, to 10 insure ample capacity for water in the boilers. Two conduits 40 and 41 are connected to the side members 23 and 24 respectively so as to have communication with the upper portion of the boilers and incidentally with 15 the valve chest portions of the engine, and they extend rearwardly in imitation of exhaust pipes and thence downwardly in the hull and outwardly through the sides of the hull, and have outer portions 42 and 43 re- 20 spectively that extend rearwardly adjacent to the stern of the boat and preferably ex- tending upwardly.

Provision is made for conveniently heating 25 water in the boilers, heat being applied under the crown portions of the fire-box by means of a reservoir or fount comprising two side walls or plates 44 and 45 connected together and extending upward di- 30 vergently so as to constitute a narrow bot- 35 tom, end members 46 and 47 and a top 48 preferably provided with a burner tube 49, if liquid fuel is preferred, through which a wick 50 extends to conduct alcohol or other suitable liquid to the upper end of the wick 55 where combustion occurs, the burner tube being relatively near to one end of the reservoir. The top 48 has a filling tube 51 ad- 40 jacent to the opposite end of the reservoir and it has a perforated cap 52 thereon. The 45 reservoir is arranged so as to be guided partly by the fire-box walls 9 and 10, and the reservoir has guide plates 53 and 54 ar- 50 ranged rearward of the lower portion there- 55 of that are supported and guided on the bottom portions 2 and 3 respectively of the hull, the plates 53 and 54 being connected together behind the reservoir and extending rearward therefrom, being secured at the rear end 47 and braced by means of a stair- 50 way 55.

A suitable cabin 56 is arranged on the side 55 portions 38 and 39 of the deck, and prefer- ably the roof of the cabin has an extension 57 connected to the partition 35 from which a forward deck 58 extends so as to cover the bow portion of the hull.

When a reservoir requires to be supplied 60 with fuel the cabin is lifted from place so that the filling tube 51 becomes accessible; and when the wick needs trimming the reser- 65 voir may be drawn rearward slidingly until the wick can be reached through the opening in the deck. The boilers may be sup- 70 plied with water at any time by holding the 85 boat in proper position and pouring the

water into the conduits, and obviously each boiler may be provided with a filling hole which must be tightly sealed after supplying the boiler with water.

In practical use a flame is produced at 70 the top of the wick 50, some of the heat passing up into the space between the "en- gine" portions of the boilers resulting in the conversion of some of the water into steam which rises into the upper portion of 75 the boilers. The steam passes out through the conduits and on coming into contact with the cool water in which the boat is floating rapidly condenses and causes a par- 80 tial vacuum in the conduits, the action being 85 independent in the different conduits, with the result that water is drawn in through each conduit and meets the hot water in the boiler in which reaction occurs, so that while the partial vacuum exists the heated water 90 expands and drives out the water from the conduit, followed by hot vapor or steam which condenses when coming into contact with the water as before. The complete 95 cycle is repeated indefinitely until the heat becomes exhausted. The water is drawn from all angles into the ends of the terminals 42 and 43 of the conduits and does not affect the movement of the boat, but the charge of water is forced out from each con- 100 duct in a solid stream with great force into the surrounding water in which the boat is floating, which forces the boat forward. The pulsations in operation cause the boiler to vibrate, especially the straight or plane parts 13 and 14, as diaphragms, being com- 105 posed of thin sheet metal, producing sounds similar to the sounds of the exhausts from an explosion engine. The charges forced out from the conduits, especially when the terminals 42 and 43 extend upwardly, cause 110 waves on the surface of the water, as indicated by a broken line on Fig. 1. When it is desired to discontinue operations the reser- 115 voir may be drawn rearward to permit the flame to be blown out, and the boiler will remain charged with water ready to resume operation when desired.

Having thus described the invention, what is claimed as new is:

1. A power-propelled boat including a hull, two boilers in the hull spaced apart and having each a vibratory wall plate, the lower portions of the boilers being secured to the hull, a cap connected to the tops of the two boilers and covering the space be- 120 tween them, two pipes connected to the upper portions of the boilers respectively and extending downwardly in and rear- 125 wardly through the hull, and a fuel reser- 125 voir having a wick-fed burner between the boilers.

2. A power-propelled toy boat including a hull, two boilers in the hull having rela- 130 tively spread-apart lower portions and up-

right upper portions, portions of the outer sides of the upper portions of the boilers being vibratory, two pipes connected with the upper portions of the boilers respectively and extending downwardly and rearwardly in the hull and divergently out through the sides of the hull, the pipes having portions outside the hull extending rearwardly and upwardly, and a fuel reservoir movably arranged between the lower portions of the boilers and having a wick-fed burner on the top thereof.

3. A power-propelled boat including a hull, two boilers having lower side portions arranged upon the bottom of the hull and extending upwardly each towards the other, each boiler having an upright upper portion spaced apart each from the other, the adjacent side walls of the upper portions being vibratory, the outer walls of the upper portions having fluted portions, two pipes connected with the upper portions of the outer walls of the boilers respectively and extending downwardly in and rearwardly through the hull, and a fuel reservoir movably guided upon the bottom of the hull between the lower side portions of the boilers and having a burner on the top thereof.

4. A toy boat comprising a hull with a stern, two transverse walls in the forward portion of the hull, a fore deck connected to the forward one of the transverse walls and to the bow of the hull, an aft deck connected to the stern portion of the hull and having narrow side portions extending to the rearward one of the transverse walls, a cabin removably supported on the aft deck against the rearward one of the transverse walls, two boilers arranged in the hull between the transverse walls, the lower portions of the

boilers being spaced apart and having crown portions together forming an arch, a reservoir in the lower portion of the hull and partially under the crown portions of the boiler and partially under the cabin, the forward portion of the top of the reservoir having a burner thereon and the rearward portion having a filling tube, and two pipes connected with the upper portions of the boilers respectively and extending through the rearward one of said walls and through the cabin and downwardly and rearwardly in the hull, the pipes having portions extending out through opposite sides respectively of the hull and thence rearward outside the hull.

5. In a boat-propelling apparatus, the combination with a hull, of a pair of boilers arranged in the hull and comprising each an inner wall and an outer wall and heads connected to the walls, the lower portions of the walls being secured to the opposite sides of the hull and inclined and curved to extend over towards those of the other boiler, the upper portions of the walls being vertical, each of the boilers having a vibratory wall portion, vertical portions of the inner walls being spaced apart and the space being provided with a cover, two pipes connected with the upper portions of the boilers respectively and extending rearwardly through the hull, and a fuel reservoir movably guided in the hull and having a burner arranged between the lower portions of the boilers.

In testimony whereof, we affix our signatures.

CHARLES J. McHUGH.
DURWARD S. RIVERS.
